US00D952478S

(12) **United States Design Patent** (10) Patent No.: **US D952,478 S**
(45) Date of Patent: **** May 24, 2022**

(54) **INFRARED ELECTRONIC THERMOMETER**

(71) Applicant: **Shenzhen Great Power Innovation and Technology Enterprise Co., Ltd.**, Shenzhen (CN)

(72) Inventor: **Winston Feng**, Shenzhen (CN)

(73) Assignee: **SHENZHEN GREAT POWER INNOVATION AND TECHNOLOGY ENTERPRISE CO., LTD.**

(**) Term: **15 Years**

(21) Appl. No.: **29/751,551**

(22) Filed: **Sep. 22, 2020**

(51) LOC (13) Cl. **10-04**

(52) U.S. Cl. **D10/57**
USPC ....

(57) **CLAIM**

The ornamental design for an infrared electronic thermometer, as shown and described.

DESCRIPTION

FIG. 1 is a front view of the infrared electronic thermometer showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.
